UNITED STATES PATENT OFFICE.

WILLIAM F. ZABRISKIE, OF DETROIT, MICHIGAN, ASSIGNOR TO GABRIEL STEEL COMPANY, OF DETROIT, MICHIGAN, A CORPORATION OF MICHIGAN.

FIRE-RESISTING FLOOR CONSTRUCTION.

Application filed June 22, 1925. Serial No. 38,846.

The invention relates to floor constructions being more particularly designed for use as first floors of buildings which are not of fire-proof construction. It has been found that 5 the majority of fires in such buildings originate in the basement and if prevented from breaking through the first floor, will do little damage. I have, therefore, devised a comparatively inexpensive floor construction 10 which, while not wholly incombustible and fireproof, is nevertheless highly resistant to fires. The invention consists in the novel construction as hereinafter set forth.

In the drawings; 15 Figure 1 is a vertical section through my improved construction, and Figure 2 is a sectional perspective view of a portion thereof.

A are the floor joists which are preferably 20 formed of metal structural shapes such, for instance, as the channel bars illustrated. These joists may, if desired, be trussed or reinforced by auxiliary bars B which are electrically welded or otherwise secured there- 25 to and are bent to form the lower chord member of the truss with intermediate bars C forming the webbing. D are nailing strips preferably secured to the flat side of the joists A by suitable means such as the nails E passing 30 through apertures in the web of said joists. These strips may be bent as at F to pass around the reinforcing bars B and C at the points of attachment between same and the joists A. G is a sheathing formed of a high- 35 ly fire-resistant material preferably composed of alternate layers of mineral and fibrous material. This sheathing is laid upon the joists and is covered by the lower or rough flooring H which latter is secured by nailing to the strips D. I is the finished flooring overlying 40 the flooring H and being laid and nailed thereto in the usual manner.

With the construction as described, the only combustible material which is exposed on 45 the underside of the floor is that formed by the nailing strips D and as these are pro-

tected on one side by the joists A and on the top by the sheathing G, there is little danger of ignition. In case any one of these nailing strips should be ignited, it is prevented from 50 freely burning by the proximity of the joists A and sheathing G so that the only damage would be charring of the exposed surfaces. The wooden superstructure including the 55 floors H and I is thoroughly protected from any fire below first by the excellent heat insulating properties of the sheathing G; second because of protection from direct access of the flames and third, by the exclusion from 60 the lower surfaces of the air necessary to support combustion. The structure therefore greatly lessens fire hazard and is nevertheless of such a character that it may be built at a cost but slightly in excess of the ordinary 65 combustible construction.

If it is desired to add a further element of protection, a ceiling of metallic lath and plaster may be arranged below the floor joists as indicated at J, Figure 1.

What I claim as my invention is:

1. A fire resisting floor construction comprising metallic joists, wooden nailing strips secured to said joists, a sheathing formed of heat insulating material overlying said joists and completely covering the spaces therebetween, and a wooden flooring laid upon said 75 sheathing in direct contact therewith and nailed through said sheathing to said nailing strips.

2. A fire resisting flooring comprising metallic joists having nailing strips secured to the sides thereof, a sheathing of incombustible heat insulating material overlying said joists and completely covering the spaces therebetween, a rough wooden flooring laid on said 85 sheathing in direct contact therewith and nailed through the same to said nailing strips and a finished flooring laid upon and nailed to said rough flooring.

In testimony whereof I affix my signature.

WILLIAM F. ZABRISKIE.
